UNITED STATES PATENT OFFICE

2,665,507

IRONING BOARD SUPPORTING STRUCTURE

Charles T. Gilbert, Saginaw, Mich., assignor to
 Saginaw Manufacturing Company, Saginaw,
 Mich., a corporation of Michigan

Application May 24, 1951, Serial No. 228,080

5 Claims. (Cl. 38—117)

1

This invention relates to table supporting structure and particularly relates to gripping mechanism by which an ironing board with foldable supporting structure may be held in raised position without the use in said supporting structure of catches or latches.

In collapsible supporting structures for ironing boards, and similar articles, it has long been customary to provide means by which a collapsible, jointed, structure is converted into a non-collapsible, immovable, structure by the fixing of one of said movable parts immovably with respect to another part. The particular means by which said one part is fixed immovably with respect to said other part has long been a subject of much attention and many devices have been proposed for accomplishing this purpose. Frequently, said first member is made slidable with respect to said second member and latch or catch means are provided for preventing sliding of said one member on said second member in either direction until said latch or catch is manually released. Such devices have the advantage of being positive in their action, but they have the disadvantage of requiring special apparatus to effect the desired latching functions and accordingly are expensive to fabricate and sometimes not entirely satisfactory in operation. Other devices have employed a slider comprising a split ring in which the material adjacent the edges of the split portion of the ring is utilized to develop sufficient friction at a predetermined point in the relationship of said one member with respect to said second member to prevent further sliding. This device likewise is effective and reasonably satisfactory but it also contains certain disadvantages in operating and in manufacture which makes further simplification desirable.

Accordingly, it is a principal object of this invention to provide means adaptable to use in combination with a collapsible supporting structure for an ironing board, or similar device, which will eliminate the useful latches or catches and yet be positive and certain in its operation.

A further object of the invention is to provide a fastening device, as aforesaid, which will be of extreme simplicity.

A further object of the invention is to provide a fastening device, as aforesaid, which will be economical to fabricate.

A further object of the invention is to provide a device, as aforesaid, which will be sturdy and will be able to withstand an amount of improper use and yet continue to function correctly.

Other objects and purposes of the invention

5 will be apparent to persons acquainted with apparatus of this general type upon reading the following disclosure and inspection of the accompanying drawings.

In the drawings:

Figure 1 represents a side elevation of an ironing board utilizing my collapsible supporting structure shown in raised position and from the side thereof.

10 Figure 2 represents a bottom view of said ironing board structure showing in solid lines the supporting means in their raised position and showing in broken lines the supporting means in collapsed position.

Figure 3 is a fragmentary view showing one detail of the slider means in two positions with respect to the front leg.

15 Figure 4 represents a section taken on the line IV—IV of Figure 3 and showing further details of the slider structure.

General construction

In general, my invention relates to the arrangement of collapsible leg structure and the provision therewith of a gripping device so mounted that: (1) when said structure is in its raised position the forces acting between said movable parts are such that no force urging said parts to move in structure collapsing direction is generated and (2) a load on the table creates effective forces which generate a frictional gripping of one part by another part by which to assure further and greater stability of the table, (3) when said load is removed said additional gripping force is removed but sufficient remains to prevent collapsing of the table, and (4) when the structure is manually moved a short distance in its collapsing direction, the arrangement of said parts is then such that very little friction exists and movement of the parts in the collapsing direction may be continued readily. More specifically, the invention contemplates a three legged structure, each leg being pivoted with respect to the table, and a pair of brace members pivoted at their respective one ends intermediate the ends of each of two of said legs and pivotally connected at their other respective ends to a slider. Said slider encircles the third of said legs in sliding relationship therewith. Said slider is made somewhat larger than the leg which it encircles by which to permit some cocking with respect thereto and the said brace members are connected to said slider somewhat off center with respect thereto. Said brace members also converge as they approach said slider so that when said table is subjected to load and said brace

members are placed under compressive stress, there will be both a compressive gripping by the sides of said slider against the leg encircled thereby as well as a biting into said leg by the slider as it becomes cocked out of parallelity with respect to said leg. Thus, the greater the load that is placed on said table the greater will be the frictional forces holding said slider in place, and when said load is removed and the slider is to be manually moved along said leg, the force required to retract said movement will be relatively small.

In the following detailed description, for purposes of convenience the terms "upper" and "lower" will be freely used and will refer to the parts of the device, or directions concerned, when the device is in its normal position of use. The terms "forwardly" and "rearwardly" and the terms "leftwardly" and "rightwardly," will be alternatively used and will refer to the leftward and rightward, respectively, parts of the device when appearing as shown in Figure 1 of the drawings.

Detailed description

Referring now to the drawings in detail, Figure 1 shows the structure of the invention applied to an ironing board 1. Said ironing board is supported by a pair of rearward legs 2 and 3 pivotally supported at their upper ends 5 and 6 adjacent the rearward corners 7 and 8 of said ironing board. Said legs are preferably arranged slightly divergent with respect to each other but this arrangement forms no part of the invention. A forward leg 9, is of U-shaped cross-section opening rearwardly, is pivotally positioned about midway between the rearward and forward ends of said ironing board, is of such length that when it occupies a position approximately 65 degrees to the horizontal and the rearward legs are substantially perpendicular with respect to the horizontal, the table will be supported in a substantially horizontal position. A pair of brace members 10 and 11 are pivotally affixed at their rearward ends to said rearward legs at points substantially intermediate the ends of said respective rearward legs. Said brace members are likewise pivotally affixed at their forward ends to the opposite sides of said forward leg 9 at a point 16 near its lowermost extremity.

A pair of control members 17 and 18 are pivotally affixed at their rearward ends to said rearward legs at points thereon substantially intermediate the ends of said rearward legs, and said points may conveniently be the same points as those at which the said brace members are affixed to said rearward legs. The forward ends of said control members are pivotally affixed by the rivet 15 on either side of a slider member 21, said slider comprising a loop portion 22 conforming to the shape of said forward leg and a tab portion 23. Said control members are affixed to said slider at a point 24 which is displaced from the center of said tab portion in a direction toward the lowermost end of said forward leg.

The forward side 26 of said forward leg is shown in Figure 4 as rounded through substantially 180 degrees. The slider is shown as similarly rounded to conform thereto. While this is the convenient, and normally preferable, structure, it arises primarily from the ease with which parts of such shape may be fabricated and does not comprise any essential portion of the invention. Said forward leg and said slider may be fabricated in any convenient shape providing only there is provided a substantial surface of contact between the for-

ward surface of said leg and the surface of said slider facing same for reasons appearing hereinafter.

Said legs are so proportioned with respect to each other and their points of pivoting with respect to each other and with respect to the ironing board 1 are such that when said supporting structure of said board is in its fully raised position, as appearing in Figure 1, the control rods 17 and 18 will be substantially perpendicular to the forward leg 9. In such position the slider 21 and the control rods 17 and 18 will assume the position shown in solid lines in Figure 3. This causes the lower edge 14 of the slider to bite into the rearward edges 19 and 20 of the forward leg 9 in the manner to effect a very reliable frictional gripping thereof.

With reference to the drawing, Figures 2 and 4, it will be seen that as the structure is erected the control rods 17 and 18 are spread (hidden edges show the collapsed structure) at the ends remote from pivotal connection to the slider 21. The maximum spreading occurs when the structure is fully erected. This spreading action causes a response of the ends of the control rods 17 and 18 against the sides of the tabs 23 causing the tabs 23 to be squeezed together constricting the loop portion 22 upon the forward leg in the manner of a clamp. This clamping or squeezing action achieves its maximum effect upon full erection of the structure and complements the biting action achieved by the offset positioning of the pivotal connection upon the tabs 23, the clamping and biting occurring at the preselected position desired.

Further, with a compressive load being placed on the control rods 17 and 18, said rods will hold the two flanges of the tab 23 firmly together and thus hold the sides 27 and 28 firmly together and against the sides of the leg 9 adjacent the ends 19 and 20.

Thus, when said table becomes loaded, the forces acting between the control rods 17 and 18 and the forward leg 9 urge the edge 14 with progressively greater force against the edges 19 and 20 of the forward leg 9, and simultaneously the sides 27 and 28 are similarly pressed against the sides of the forward leg 9 adjacent said rearward edges thereof 19 and 20. These forces, together with the fact that the thrust of said control rods 17 and 18 is substantially perpendicular to the longitudinal centerline of the forward leg 9 makes it impossible for said slider to move downwardly along said leg and thus the supporting structure for said table is firmly and rigidly held in table supporting position.

However, when the load is removed from said table, the gripping forces imposed onto the slider are simultaneously removed and it can be easily moved by hand downwardly toward the lower extremity 16 of said forward leg 9. Because of the large surface between the forward portion 29 of the slider and the corresponding forward portion 26 of the forward leg 9, this sliding will be easily effected merely by pulling the lower end of said leg 9 forwardly after the slider has moved a short distance, approximately one-fourth to one-third of the length of said leg, away from the upper end thereof. This materially facilitates the collapsing of the leg structure.

It will be thus appreciated that I have provided a structure capable of accomplishing the various objectives above set forth.

It will be recognized that numerous variations may be made from the specific structural de-

tails appearing in the particular embodiment herein chosen for illustrative purposes, and excepting as the hereinafter appended claims specifically require otherwise, said structural variations will be included within the scope of said hereinafter appended claims.

I claim:

1. In collapsible structure for supporting a panel in substantially horizontal position, having a pair of legs pivotally affixed near the rearward corners of said panel, a leg pivotally affixed at a point intermediate the ends of said panel and of substantially greater length than said first two named legs, a pair of brace members pivotally affixed intermediate the ends of said rearward legs and pivotally affixed at their forward ends near the forward extremities of said forward leg, a pair of control members pivotally affixed intermediate the ends of said rearward legs and extending toward said forward leg, slider means affixed to the forward end of said control members and slidably engaging said forward leg, all of said members being so proportioned and their points of fastening to said panel being so spaced with respect to the lengths of said members that when the free ends of said leg members define a plane substantially parallel to said panel said control members will be substantially perpendicular with respect to said forward leg; the improvement in said slider and forward leg construction comprising: said forward leg having a substantially U-shaped cross-section and positioned to open toward said other two legs; said slider encircling said forward leg and having those walls thereof which face said forward leg contoured substantially similarly thereto, and comprising a clamping loop portion encircling said forward leg having tab portions extending rearwardly from said loop, said tabs being spaced apart from each other in generally parallel relationship to each other and pivotally affixed, offset from the geometric center of said tabs, to the forward ends of said control members; said loop being larger in a direction parallel to the flanges of said U-shaped forward leg than the corresponding dimension of said U-shaped forward leg and extensions of said forward ends of the control members bearing against the said tabs of said loop in the manner of a clamp.

2. The device defined in claim 1 wherein the 50

point of pivotal connection between said tabs and the forward ends of said control members is located at a point between the longitudinal center line of said slider and the edge thereof remote 5 from said table.

3. The device defined in claim 1 wherein the sides of said slider converge in a direction toward said tabs sufficiently to engage the free edges of said U-shaped member.

10 4. In collapsible structure for supporting a panel in a preselected position, and including a first part movably positioned with respect to a second part, means selectively holding said parts against movement comprising: the improvement a
5 in said slider and forward leg construction comprising: said second part having a substantially U-shaped cross-section and positioned to open toward said first part; said slider encircling said second part and having those walls thereof which face said second part contoured substantially similarly thereto, and comprising a loop portion encircling said second part and tab portions extending rearwardly from said loop, said tabs being spaced apart from each other in generally parallel relationship to each other and pivotally affixed, offset from the geometric center of said tabs, to the adjacent ends of said first part; said loop being larger in a direction parallel to the flanges of said U-shaped second part than the corresponding dimension of said U-shaped second part; and means at the ends of said first parts whereby said tabs may be pressed together clamping said loop portion of said slider upon said forward leg at a prearranged point.

5. The device defined in claim 1 wherein at the point of final convergence of the said slider with the free edges of the U-shaped leg, the slider is tilted out of parallel with respect to said U-shaped forward leg so as to exert a biting action 0 on the free edges of the said U-shaped forward leg.
